UNITED STATES PATENT OFFICE.

MINNIE M. DICKINSON, OF EVANSTON, ILLINOIS.

TRUCK.

Specification of Letters Patent. Patented Aug. 24, 1909.

931,849.

Application filed April 30, 1906. Serial No. 314,338.

To all whom it may concern:

Be it known that I, MINNIE M. DICKINSON, a citizen of the United States, residing at Evanston, in the county of Cook and 5 State of Illinois, have invented certain new and useful Improvements in Trucks, of which the following is a specification.

My present invention relates to improvements in trucks and has for its object the 10 provision of a light, strong and convenient truck for tubs used for the washing of clothes and other purposes and is useful not only for the purpose of conveying the heavy 15 filled tubs from place to place but also provides a convenient stand for the tubs while in use.

To the accomplishment of the above objects my invention consists of a new and novel structure and combination of parts as 20 will presently appear.

In the drawings:—Figure 1 is a perspective view of my new truck supported by three standards or legs. Fig. 2 is a perspective view of my new truck supported by 25 four standards or legs. Fig. 3 is a perspective view of the truck shown in Fig. 2 supporting a tub.

The numeral 1 designates the legs or standards which are attached to the sides 2 of the top with the bolts or rivets 3. At 30 about the middle of the standards or legs 1 I provide the bracing hoop or band 4 which secures great rigidity of structure and upon the lower extremity of the legs or standards 35 1 I provide the casters or rollers 5. The top of my truck which is the special

feature desired to be secured consists of a ring of suitable diameter of practically L shaped cross-section wherein the standing portion or side 2 of said ring or top surrounds the bottom portion of the sides 6 of the tub to prevent it from slipping and the lying or horizontal portion 7 of said ring or top receives and supports the bottom of the tub. This structure of top has numerous 40 advantages among which are a minimum of weight coupled with a maximum of strength and rigidity while at the same time the sides 2 clasp the tub against displacement while in use or from rough handling or accident. 45

From the foregoing description, taken in connection with the drawings, it is evident that I provide a truck suitable for tubs extremely simple in construction and effective 50 in operation.

What I claim as new and desire to secure by Letters Patent is:—

In a portable truck, the combination of a base comprising a plurality of legs having casters therein, a brace surrounding said 60 legs and rigidly secured thereto, a tub seat arranged on top of said base, said tub seat being circular and angular in cross section to support the bottom and sides of a tub placed thereon, substantially as described. 65

In testimony whereof I affix my signature in presence of two witnesses.

MINNIE M. DICKINSON.
